WALL HUNG CLOTHES HAMPER OR SIMILAR ARTICLE

William D. Taylor, Wooster, Ohio, assignor to Rubbermaid Incorporated, Wooster, Ohio, a corporation of Ohio

Filed Apr. 24, 1962, Ser. No. 69,836

Term of patent 14 years

(Cl. D58—4)

FIG. 1

FIG. 2

FIG. 3

FIG. 4

FIG. 5

FIG. 6

FIG. 1 is a perspective view of the wall hung clothes hamper embodying my new design;

FIG. 2 is a right side elevational view thereof;

FIG. 3 is a fragmentary cross section thereof taken along line 3-3 of FIG. 1;

FIG. 4 is a rear elevational view thereof;

FIG. 5 is a top plan view thereof;

FIG. 6 is a bottom plan view thereof.

I claim:

The ornamental design for a wall hung clothes hamper or similar article, substantially as shown.
